(57) CLAIM

The ornamental design for a bath scrubber, as shown and described.

DESCRIPTION

FIG. 1 is a top perspective view of a bath scrubber having a hive shaped handle embodying my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines illustrate unclaimed portions of the bath scrubber that form no part of the claimed design.
